UNITED STATES PATENT OFFICE.

WILLIAM WAYNE HALLINAN, OF PUEBLO, COLORADO.

AIR INSPIRATOR FOR ENGINES.

Application filed December 13, 1922. Serial No. 606,709.

To all whom it may concern:

Be it known that I, WILLIAM W. HALLINAN, a citizen of the United States, residing at Pueblo, in the county of Pueblo and State 5 of Colorado, have invented certain new and useful Improvements in an Air Inspirator for Engines; and I do hereby declare the following to be a full, clear, and exact description of the invention, such as will enable others skilled in the art to which it 10 appertains to make and use the same.

The present invention relates to an air inspirator for internal combustion engines, and aims to provide a novel and improved 15 device for admitting an auxiliary supply of air to the carbureted air flowing from the carbureter to the intake manifold of the engine, in order to dilute the mixture and obtain more efficient combustion of the fuel, 20 especially when the throttle valve is opened to enrich the mixture.

Another object is to combine the air entry means with the throttle valve, whereby the admission of air to the mixture flowing 25 from the carbureter to the engine is controlled according to the position of the throttle valve, to proportion the auxiliary supply of air according to the position of such valve.

30 A further object is the provision of a throttle valve construction having novel means for the passage of a restricted stream of carbureted air, when the throttle valve is closed, for the idling operation of the engine.

35 A still further object is the provision of such a device incorporating the throttle valve, by-pass arrangement and auxiliary air inlet means into a unit which can be readily disposed or sandwiched between the carbureter and intake manifold of an engine.

40 It is also an object of the invention to provide such a device which is simple and inexpensive in construction, as well as being practical and efficient in use.

45 With the foregoing and other objects in view, which will be apparent as the description proceeds, the invention resides in the construction and arrangement of parts, as hereinafter described and claimed, it being 50 understood that changes can be made within the scope of what is claimed, without departing from the spirit of the invention.

The invention is illustrated in the accompanying drawing, wherein—

55 Figure 1 is a side elevation of the improved device.

Fig. 2 is a section on the line 2—2 of Fig. 1, showing the device in plan.

Fig. 3 is a section on the line 3—3 of Fig. 1.

60 The improved device, which is constructed as a single unit, is disposed between the carbureter and intake of the engine cylinders, the numeral 7 designating the outlet portion of the carbureter and the numeral 65 8 the trunk or inlet portion of the intake manifold, said carbureter and manifold having the flanges 9 and 10, respective, which are usually clamped or fastened together. However, in using the present device, it is 70 readily interposed between the carbureter and manifold by placing it between the flanges 9 and 10 when said carbureter and manifold are separated.

75 The device comprises a block or body 11 which is sandwiched or disposed between the flanges 9 and 10, and said flanges and body are clamped together by bolts 12. The body has an opening 13 of the same diameter as the openings or bores of the adjacent 80 ends or portions of the carbureter and manifold, and between the extremities of the opening or passage 13, the body 11 is formed within said opening with a crescent-shaped flange or ledge 14 forming a secondary 85 opening 15 smaller in diameter than the main opening 13 and eccentric relatively to said opening 13, with the openings 13 and 15 tangent at a point opposite to the intermediate portion of the flange 14. The flange 90 14 provides the oppositely-facing upper and lower shoulders 16.

95 The throttle valve 18 is disposed in the opening 15, and is secured on a rock shaft 17 which is journaled through the body or member 11 and the flange 14 intermediate the ends of the flange, an arm 19 being secured to one protruding end of said shaft for turning the shaft to open and close the throttle valve. The throttle valve 18, when 100 closed, fits snugly within the flange 14, to close the opening 15, and the throttle valve 18 is used in lieu of the usual throttle valve in the outlet portion of the carbureter, or such throttle valve of the carbureter is fastened wide open. In other words, instead of using the customary throttle valve, the throttle valve of the present device is substituted, being located higher up.

105 In order to permit a restricted amount of carbureted air to pass the throttle valve when said valve is completely closed, so that

the engine can continue to operate idly, the flange 14 is provided at its intermediate or wider portion with the by-pass ports 20 and 21 extending therethrough from one shoulder 16 to the other, said ports being located at opposite sides of the shaft 17. The port 20 permits a stream of carbureted air to flow therethrough, while the flow through the port 21 can be regulated, in order to adjust the amount of carbureted air that is allowed to pass the throttle valve with said valve in closed position. Thus, a screw valve 22 is threaded into the body 11 to project into the port 21, for closing said port more or less, to restrict or shut off the flow of air through the port 21. However, the port 20 will remain open at all times, even though the valve 22 is completely closed, so as to assure of sufficient carbureted air flowing past the throttle valve to keep the engine idling.

The body 11 has a flat face or abutment 23 at one side, from which air entry ports 24 and 25 extend to the opening 13 above the flange 14, whereby air can flow from the atmosphere through said ports, when opened, to mix with the carbureted air flowing past the throttle valve.

The inlet of air through the ports 24 and 25 is controlled by a shutter 26, which comprises a flat plate of metal bearing snugly against the face of the abutment 23, said shutter being engaged on a squared or non-circular portion 27 of the shaft 17 to turn said shutter with the throttle valve. A coiled spring 28 surrounds the shaft 17 and is confined between the shutter 26 and a nut 29 screw-threaded on the protruding stem of the shaft 17, whereby to press the shutter 26 under tension against the abutment 23, thereby not only keeping the shutter tightly in place but also providing a friction means for holding the shutter and throttle valve in any position to which they are turned. When the shutter 26 is in its initial position, with the throttle valve closed, the shutter extends across and closes the outer ends of the ports 24 and 25. The shutter has an eccentric curved edge 30 extending from the port 25 counterclockwise nearer to the axis of the shaft 17 and shutter, whereby when the shutter is turned in opening the throttle valve, the port 25 will be gradually uncovered as the edge 30 moves across said port, thereby gradually accelerating the amount of air which can pass through the port 25. The shutter 26 has an offset or cut-away portion 31 immediately adjacent to the port 24, in order that the port 24 will be uncovered or opened as soon as the throttle valve is opened slightly, thereby immediately permitting the air to flow through the port 24, and as the throttle valve is opened further, the port 24 is gradually opened.

The speed of the engine is controlled, as usual, by the opening and closing of the

throttle valve, and when the throttle valve is completely closed, for the idling operation of the engine, sufficient carbureted air can flow through the by-pass ports 20 and 21 with the engine running. During such idling of the engine, the air entry ports 24 and 25 are both closed, but the moment the throttle valve is opened slightly the port 24 is uncovered or opened, thereby admitting an auxiliary stream of air which mixes with the carbureted air flowing past the throttle valve. The further the throttle valve is opened to move the edge 30 across the port 25, the more air is permitted to flow through the port 25, thereby accelerating or increasing the admission of air. The primary port 24 is opened immediately when the throttle valve is opened slightly, while the secondary air inlet port 25 is opened gradually after the port 24 has been opened during the further opening of the throttle valve.

The present device induces more air into the carbureted mixture, in order to improve the combustion of the fuel, with a saving in fuel and an increased efficiency of the engine, as well as greater mileage for the fuel consumed. The formation or accumulation of carbon in the engine cylinders is also reduced. The throttle valve being located higher up will give the globules of fuel an opportunity to drop back before passing the throttle valve, so as to return to the carburetor. The flange 14 also provides a baffle or obstruction which will arrest the upward creeping of the fuel along the wall of the intake conduit with the flow of air, so that the passage of unvaporized fuel to the engine cylinders will be eliminated, thereby avoiding dilution of the crank case oil as well as preventing the formation of carbon by the over supply of fuel to the combustion chambers. The additional supply of air will render the mixture thoroughly combustible, and the admission of air through the ports 24 and 25 will also serve to reatomize the heavier and condensed portions of the fuel flowing along the sides or wall of the intake conduit, it being noted that the ports 24 and 25 are tangent, or substantially tangent, to the opening 13 above the flange or baffle 16, whereby the inflowing streams of air will whirl or agitate the mixture above the wings of the butterfly throttle valve 18.

Although the present device is shown as a separate unit, to be disposed between the carburetor and intake manifold, it can be built in or incorporated as a part of the carburetor, in which case the body or member 11 would be a part of the carburetor construction.

Having thus described the invention, what is claimed as new is:—

1. A device of the character described comprising a body having an opening for

the flow of carbureted air to an engine, and having a flange within said opening, and a throttle valve mounted in said opening to fit said flange when the valve is closed, said flange having a by-pass port therethrough.

2. A device of the character described comprising a body having an opening for the flow of carbureted air to an engine, and having a flange within said opening, a throttle valve mounted in said opening to fit said flange when the valve is closed, said flange having a plurality of by-pass ports therethrough, and means for controlling the flow through one of said ports.

15 3. A device of the character described comprising a body having an opening therein for the flow of carbureted air to an engine, and having a crescent-shaped flange in said opening providing a smaller secondary opening, and a throttle valve mounted in said secondary opening, said flange having a by-pass for the air.

4. A device of the character described comprising a body having an opening for the flow of carbureted air to an engine, a shaft extending through said body, a throttle valve carried by the shaft in said opening, the body having an air entry port leading to said opening, a shutter to extend across said port bearing against the exterior of said body and rotatable with said shaft, and spring means on said shaft pressing said shutter against the body, the shutter being cut away so as to uncover the port when the shutter is turned in opening said valve.

35 5. A device of the character described comprising a body having an opening for the flow of carbureted air to an engine and having primary and secondary air entry ports leading to said opening, and a shutter for said ports having a portion for completely opening the primary port by a slight movement of the shutter and having an eccentric portion to gradually open the secondary port when the shutter is moved further.

40 6. A device of the character described comprising a body having an opening for

the passage of carbureted air to an engine, a throttle valve mounted in said opening, 50 said body having primary and secondary air entry ports leading to said opening, and a shutter for said ports movable with the throttle valve and having a portion to completely open the primary port when the 55 throttle valve is opened slightly, the shutter having an eccentric portion for opening the secondary port gradually as the throttle valve is opened further.

7. A device of the character described 60 comprising a body having an opening for the passage of carbureted air to an engine, a baffle in said opening, and an air entry port leading to said opening adjacent to said baffle, said baffle providing an obstruction to 65 the flow of fluid along the wall of said opening.

8. A device of the character described comprising a body having an opening for the passage of carbureted air to an engine, a 70 throttle valve mounted in said opening, said body having a baffle in said opening to fit said valve when the valve is closed, and the body having an air entry port extending to said opening adjacent to said baffle, said 75 baffle providing an obstruction to the flow of fluid along the wall of said opening.

9. A device of the character described comprising a body having an opening for the passage of carbureted air to an engine, 80 and a throttle valve mounted in said opening, said body having a baffle in said opening to fit the valve when the valve is closed, and the body having an air entry port leading to and arranged substantially tangentially with said opening adjacent to said baffle, said baffle providing an obstruction to 85 the flow of fluid along the wall of said opening.

In testimony whereof I have signed my 90 name to this specification in the presence of two subscribing witnesses.
